ELASTIC SANITARY TELEPHONE
PROTECTOR

Godel Kalenoff, Brooklyn, N. Y.

Original application November 27, 1934, Serial
No. 754,941. Divided and this application Au-
gust 2, 1935, Serial No. 34,336

2 Claims. (Cl. 179—185)

This invention relates to improvements in sanitary protectors for telephone transmitters and receivers, and its leading object is to provide a simple, inexpensive cover for a telephone transmitter or mouthpiece, which will resiliently grip the telephone part and provide a sanitary protection for the user.

An object of the invention is the provision of a sanitary cover for telephones, having a sleeve portion adapted to be stretched over the telephone part, and an outer portion provided with a voice opening, which may be stretched over or snugly placed and held against the telephone transmitter or mouthpiece, or the receiver of the telephone.

A still further object is to provide means for simplifying the connection between the sanitary telephone cover and the telephone part engaged thereby.

With the above and other objects in view the invention consists in certain new and useful constructions, combinations and arrangements of parts, clearly described in the following specification, and fully illustrated in the accompanying drawing, in which:—

Fig. 1 is a side view, partly in longitudinal section, showing a conical transmitter mouthpiece provided with a sanitary cover.

Fig. 2 is a side view of the sanitary cover, shown in Fig. 1, removed and fully opened.

In Figs. 1 and 2 I show a form of the invention, wherein the resilient rubber cover is applied to the conical mouthpiece of a telephone transmit-

ter 17. In this case the cover 18 is made tubular, and may be formed with a conical portion 19 to enclose the mouthpiece 17, and with another conical portion 20 to snugly fit in this mouthpiece and form a sanitary facing or lining therefor. The larger ends of the two conical portions are integrally connected at 21, which corresponds with the end of the mouthpiece. The end of the conical portion 19 is formed with a terminal bead 19a, and the end of the conical portion 20 is provided with a terminal bead 20a, to aid in the mounting or positioning of the protective attachment.

The external and internal sanitary mouthpiece protector is provided with a resilient wall, which grips all exposed surfaces of the mouthpiece.

Having described my invention, I claim as new and patentable:—

1. A telephone protector, comprising a tubular body of flexible resilient material adapted to be positioned over a mouthpiece, resiliently grip the same and cover the inner and outer surfaces thereof and the outer edge thereof.

2. A telephone protector, comprising a tubular body of flexible resilient material adapted to be positioned over a mouthpiece, resiliently grip the same and cover the inner and outer surfaces thereof and the outer edge thereof, said body having beads at both ends and of greatest diameter centrally of its ends and tapering to both ends.

GODEL KALENOFF.
